UNITED STATES PATENT OFFICE

116,655

DESIGN FOR A MOTOR VEHICLE

Frederick E. Dayes, Philadelphia, Pa., assignor to
American Car and Foundry Motors Company,
New York, N. Y., a corporation of Delaware

Application December 15, 1938, Serial No. 81,802

Term of patent 7 years

To all whom it may concern:

Be it known that I, Frederick E. Dayes, a citizen of the United States, residing in the city and county of Philadelphia, State of Pennsylvania, have invented a certain new, original, and ornamental Design for a Motor Vehicle, of which the following is a specification, reference being had to the accompanying drawings, forming part thereof, in which:

Fig. 1 is a side elevation of a motor vehicle showing my new design.

Fig. 2 is an inverted plan view of the car roof showing the new design of a ceiling portion.

Fig. 3 is an enlarged fragmentary perspective view of the interior of the vehicle, the view being taken on the line 3—3, Fig. 1.

Fig. 4 is an enlarged transverse fragmentary section on line 4—4 of Fig. 3.

Fig. 5 is an enlarged transverse section on line 5—5 of Fig. 3 and

Fig. 6 is an enlarged perspective view of the ceiling panel.

The characteristic features of the design reside particularly in the ceiling of the vehicle especially as illustrated in Figs. 2 and 6 and shown in solid lines in Fig. 3 and wherein ceiling portions are formed with longitudinal corrugations extending from end to end.

I claim:

The ornamental design for a motor vehicle, substantially as shown and described.

FREDERICK E. DAYES,
